DESIGN FOR A TIRE

Charles W. Yelm, Denver, Colo., assignor to The
Gates Rubber Company, Denver, Colo., a cor-
poration of Colorado

Application April 2, 1938, Serial No. 76,238

Term of patent 14 years

To all whom it may concern:

Be it known that I, Charles W. Yelm, a citizen of the United States, residing at the city and county of Denver, and State of Colorado, have invented a new, original, and ornamental Design for Tires, of which the following is a specification, reference being had to the accompanying drawing, forming part thereof.

In the drawing:

Figure 1 is a perspective view of a tire, partly in dotted lines, showing my new design;

Figure 2 is a fragmentary plan view thereof;

Figure 3 is a cross sectional view taken on line 3—3 of Fig. 2; and

Fig. 4 is a fragmentary side elevation showing the appearance of the side wall in greater detail.

The dominant feature of the invention resides in the side wall design as presented in enlarged detail in Fig. 4.

I claim:

The ornamental design for a tire, as shown and described.

CHARLES W. YELM.
